UNITED STATES PATENT OFFICE.

ALAN MACDONALD, OF SAN FRANCISCO, CALIFORNIA, ASSIGNOR TO SAN FRANCISCO SHIP BUILDING CO., OF SAN FRANCISCO, CALIFORNIA, A CORPORATION OF CALIFORNIA.

COCOANUT-OIL BARGE.

1,284,394.

Specification of Letters Patent. Patented Nov. 12, 1918.

Application filed July 15, 1918. Serial No. 244,907.

To all whom it may concern:

Be it known that I, ALAN MACDONALD, a citizen of the United States, residing at the city and county of San Francisco and 5 State of California, have invented certain new and useful Improvements in Cocoanut-Oil Barges, of which the following is a specification.

My invention relates to barges and other 10 floating vessels for carrying vegetable-oils, principally cocoanut-oil.

It is customary in oil-barges or tank steamers to fill the holds of the vessels with the oil, so that the liquid is in contact with 15 the outside plating of the ship. Vegetable oils, such for example, as cocoanut oil which solidifies at a relatively high temperature, about 60 degrees Fahrenheit, required to be heated at the end of the voyage, so that 20 the oil cargo may be unloaded with pumps. This heating is customarily done by means of steam pipes or coils in the bottom of the vessel, immersed in the oil. This practice is unsatisfactory, due to the danger of over- 25 heating the oil, the expense of the coils and their maintenance, the difficulty of cleaning the compartments, and above all, the damage to the oil in case of steam leaks.

Moreover, in contemplating the use of 30 reinforced concrete barges and vessels as oil carriers, the fact that contact of the oil with the concrete has a damaging effect on the latter, must be taken in consideration.

It is therefore apparent that with concrete vessels the customary practice of filling 35 the hull directly with oil is impracticable and this together with the disadvantages of the usual heating by means of immersed steam pipes, makes it a matter of importance, especially with concrete hulls, to so store the oil that it shall not be in contact 40 with the concrete and also that such storage shall be of a character adapted both for inspection for oil leaks and for the use of a 45 more effective and less damaging means or method of heating the oil in order to liquefy it so that it may be discharged by pumping.

These are the objects in view and though 50 my invention is applicable to barges and vessels of wood, steel or any material, it is especially applicable to and advantageous in concrete vessels and barges, in which connection, for the sake of demonstrating its full advisability, I shall describe it, not

limiting myself, however, to such concrete 55 vessels, except in so far as specifically claimed.

In the accompanying drawings,

Figure 1 is a longitudinal section on the line 1—1 of Fig. 2. 60

Fig. 2 is a top plan view, with the deck partly broken away.

1 is the concrete hull of the barge, 2 is the concrete deck, and 3 are the concrete bulkheads, which are here shown as dividing the 65 hull into four tank-compartments, though this number may be varied as required.

In each compartment is a tank 4 of steel. These tanks rise to and fit closely up under 70 the deck, but they are of such diameters or lateral dimensions as to leave a clear space between their walls and the inner surfaces of their concrete environment. They are also set up on blocks 5 so that a space is left 75 between their bottoms and the bottom of the hull.

In the several bulkheads are made the apertures 6.

In an end compartment of the barge are assembled the following:—7 is a boiler in 80 which steam is generated. The steam is carried in a pipe 8 to an engine 9 which drives a fan 10, and said steam is thence carried into a steam coil 11 in an air box 12 said air box receiving the delivery flue 13 from the 85 fan and discharging into the first tank compartment through an opening 14. From the last tank compartment a flue 15, leads back to the fan.

Air is driven by the fan 10 into the box 12 90 and is therein heated by the steam-heated coil 11. From the box 12 the heated air circulates through all the tank compartments, as shown by the arrows and returns to the fan. In its course it passes beneath the 95 tanks and heats their contents, this bottom contact being most effective.

By this arrangement of enveloping spaces, sides and bottom, especially the latter, it is possible to heat the oil from the exterior, 100 thereby avoiding the dangers of the customary method of heating by steam pipes immersed in the oil, and though this arrangement is advantageous in any hull regardless of the material of which it is made, 105 it has the special advantage in concrete hulls of keeping the oil out of contact with the concrete. It also has the advantage of per-

mitting inspection for possible oil leaks, and of rendering it possible to clean the tanks easily.

I claim:

5. 1. A barge or other floating vessel, having bulkheads dividing the same into compartments, said bulkheads having openings therein to provide for the circulation of air through the compartments; oil tanks in the 10 compartments separated from the bottom of the compartments; means to circulate air through the compartments under the oil tanks; and means to heat the air.
15. 2. A barge or other floating vessel, having bulkheads dividing the same into compartments, said bulkheads having openings therein to provide for the circulation of air through the compartments; oil tanks in the compartments separated from the sides and 20 bottom of the compartments; means to circulate air through the compartments around the oil tanks; and means to heat the air.
25. 3. A concrete barge or other concrete floating vessel having bulkheads dividing the same into compartments, said bulkheads

having openings therein to provide for the circulation of air through the compartments; oil tanks in the compartments separated from the bottom of the compartments; means to circulate air through the compartments under the oil tanks; and means to heat the air.

4. A concrete barge or other concrete floating vessel having bulkheads dividing the same into compartments, said bulkheads 35 having openings therein to provide for the circulation of air through the compartments; oil tanks in the compartments separated from the sides and bottom of the compartments; means to circulate air through 40 the compartments around the oil tanks; and means to heat the air.

In testimony whereof I have signed my name to this specification in the presence of two subscribing witnesses.

ALAN MACDONALD.
